HORSE TRAILER

Samuel B. Miley, Fort Worth, Tex.

Application January 12, 1953, Serial No. 23,099

Term of patent 3½ years

(Cl. D14—3)

To all whom it may concern:

Be it known that I, Samuel B. Miley, a citizen of the United States of America, residing at Fort Worth, in the county of Tarrant and State of Texas, have invented a new, original, and ornamental Design for a Horse Trailer, of which the following is a specification, reference being had to the accompanying drawing, forming part thereof.

I claim:

The ornamental design for a horse trailer, substantially as shown and described.
